UNITED STATES PATENT OFFICE.

JAHAN G. CARLSON, OF ROCKFORD, ILLINOIS, ASSIGNOR TO BURSON KNITTING COMPANY, OF ROCKFORD, ILLINOIS, A CORPORATION OF ILLINOIS.

AUTOMATIC STOP FOR KNITTING MACHINES.

1,414,546.

Specification of Letters Patent.

Patented May 2, 1922.

Application filed April 23, 1920. Serial No. 376,071.

To all whom it may concern:

Be it known that I, JAHAN G. CARLSON, a subject of Sweden, residing at Rockford, in the county of Winnebago and State of Illinois, have invented certain new and useful Improvements in Automatic Stops for Knitting Machines, of which the following is a specification.

This invention pertains in general to automatic stop mechanism employed in knitting machines, and while being of general application I have in the present case, illustrated it in connection with an automatic stop device of the character disclosed in Patent No. 15 1,090,119.

Stop mechanism of this particular character are actuated generally by interruption or breaking of the yarn, rather than by the presence of a knot, lump or other obstruction carried on the yarn. Such obstructions, 20 are of course, inimical to perfect knitting.

The primary object of the present invention is to provide for the automatic stopping of a knitting machine by the presence 25 on the yarn leading to the yarn-carrier, of a knot, lump or any other obstruction. This object I accomplish by causing the obstruction to initiate the stop action, which results in immediate stopping of the machine.

30 I have also aimed to provide a stop-actuating means of this character which having been actuated by the obstruction, permits free passage thereof so as not to place such undue tension or strain on the yarn as might 35 break the same before the machine comes to a stop.

Still another object is the provision of a stop device of this character which will be of simple and practical construction and applicable as an attachment to various stop devices, and especially to those employing 40 a sensitive trip rod of the character disclosed in the patent mentioned above.

Referring to the drawing,—

45 Figure 1 is a front view of an automatic stop mechanism embodying my improvements;

Fig. 2, a side elevation thereof;

Fig. 3, a detail view of the lower end of 50 the yarn guide adapted to be actuated by an obstruction on the yarn; and

Fig. 4, a diagrammatic view illustrating the action of said lower end of the thread guide.

55 The construction in general shown in

Figs. 1 and 2, is taken from the above mentioned patent and serves simply as one example illustrating the use of my improvements in connection with a suitable automatic stop device and with suitable means 60 for guiding the yarn leading to the yarn carrier.

The drawing shows a vertical post 5 carrying a horizontal supporting arm 6 to which is secured a take-up carrying arm 7 65 and a thread guide support 8. The arm 7 carries a spring tension arm 9 equipped at its rear end with a thread-guiding eye 11 and carries also a flexible wire take-up arm 12 equipped at its forward end with an eye 70 10 through which the yarn passes to the yarn-carrier. Intermediate the take-up eye 10 and the eye 11 is interposed a yarn-holding device designated generally by character 75 13, the construction of which is immaterial to the present application. It is sufficient to state that the yarn from the spool or bobbin is drawn through the eye 11, thence through the tension or yarn checking device 13, and thence through the take-up eye 80 10 to the yarn-carrier.

In the event that the yarn should break, the take-up arm 12 would swing upwardly and actuate a very sensitive trip rod 14, which in turn sets off or causes the stop 85 mechanism to function and stop the operation. In this particular case, the trip rod is pivotally supported at its end adjacent to the post 5 and is adapted to swing at its outer end horizontally to the left, viewing 90 Fig. 2, whereby to release the holding dog 15 against which the thrust rod 16 bears upwardly. This thrust arm when released by the dog causes a clutch to be shifted for 95 breaking the driving connection to the machine. For a more thorough description of this particular stop action, reference may be had to the above mentioned patent. It should be understood, however, that my present improvements are in no way limited 100 to use this particular stop action.

Coming now to the present improvement, my invention contemplates the provision of a yarn-actuable member preferably pivoted, and shaped to provide a narrow elongated 105 opening through which the yarn normally passes but which is so restricted as to preclude the passage of a knot, lump or other obstruction on the yarn, such obstruction by contact with the pivoted member actuates 110

the same and thus by operation of the trip rod sets off the stop mechanism. In this particular instance, said member designated generally by character 17 is formed of wire 5 and pivotally mounted intermediate its ends at 18 upon a suitable support 19. The upper end 21 of said member is disposed immediately in front of the trip rod 14, so that upon swinging of said member in a counter-clockwise direction viewing Fig. 2, the rod 14 will be tripped from its set position, thus stopping the machine. The lower end of said member is shaped as shown in Fig. 3, to provide a narrow elongated opening 22 through which the yarn 23 normally passes and this opening 22 merges at its lower end into a larger opening or eye 24. The spring wire portions 25 defining the sides of the opening 22 constitute a restricted yarn guide, 20 and it will be observed that should a lump or obstruction as indicated by the character 26, Fig. 4, on the yarn be carried against the member 25, this obstruction will by the forward pull on the yarn, swing the arm 17 25 so as to initiate the stop action. Inasmuch as the yarn continues to be drawn forwardly for a short interval after the member 17 is actuated, I have so arranged and shaped said member that it will not offer complete obstruction to the knot 26, but instead will after the stop action is initiated, allow such knot to pass by, thus preventing breakage of the yarn. It will be plainly seen, viewing Fig. 4, that when the lower end of the member 17 is swung to the right by the action 30 of the knot 26, the latter will follow down said member and pass through the eye 24 at the lower end thereof. Consequently, breakage of yarn is avoided and the attendant may remove the lump or obstruction and retie the parted ends of the yarn without necessity of rethreading the yarn through the various guides.

It is believed that the foregoing conveys 45 a clear understanding of my improvement, and while I have illustrated but a single working embodiment thereof, it should be manifest that it is susceptible of consider-

able change in construction and arrangement without departing from the spirit and scope 50 of the invention as expressed in the appended claims, in which—

I claim:

1. An automatic stop mechanism including a pivoted yarn actuatable member having a portion depending from its pivot and shaped to provide a narrow elongated opening terminating at its lower end in an eye, said opening being so restricted as to prevent the passage of a knot or other obstruction, whereby the latter will actuate said member for initiating the stop action, and said eye permitting free passage of said obstruction without displacing the yarn from said member. 65

2. An automatic stop mechanism including in combination with a trip rod adapted to initiate the stop action, a spring tension arm and a take-up arm through which arms the yarn passes in succession, and a yarn-actuable member operable between said tension arm and the trip rod and having a narrow elongated opening terminating at one end in an eye, through which opening the yarn passes, said member adapted to be actuated by a knot or other obstruction on the yarn, whereby to actuate said trip rod, and said eye permitting passage of said obstruction without displacement of the yarn from said member. 70 75

3. In an automatic stop mechanism of the character described, a pivoted member adapted upon being swung away from its normal position to initiate the stop action, said member having a narrow elongated 85 thread guiding opening terminating at one end in an eye, said opening being so restricted as to prevent the passage of a knot or other obstruction, whereby the latter will move said member from its normal 90 position to initiate the stop action, and said eye permitting passage of said obstruction without displacing the yarn from said member. 80

JAHAN G. CARLSON.
